BLAST TORCH PERFORATED COMBUSTION BURNER

Samuel C. Brody, Newton, Mass.

Application July 23, 1947, Serial No. 762,970

2 Claims. (Cl. 158—33)

1

This invention relates to a novel combustion burner to be used with an automatic pressure generating unit of the self-generating type.

One object of my invention is to provide a burner which is so constructed as to greatly intensify the conduction of heat to the pressure generating tube, sometimes called a wick tube or "gooseneck," on which the burner is operatively assembled.

Another object is to provide a burner which is so constructed as to prevent leakage of gas or other pressures past the joining faces between the burner and the operating assembly of the pressure generating tube.

A further object of my invention is to provide a combustion burner that will generate a greater proportion of heat and a far more intense blast flame for a given diameter than was heretofore possible.

A still further object of my invention is to provide a burner so constructed as to furnish the means for constantly increasing combustion therein so that the blast flame emitting therefrom may quickly reach its maximum force and heat intensity in proportion to the diameter and construction of the burner and to retain and continue to generate such maximum force and blast flame until all the fuel has been exhausted or until the torch has been extinguished.

In attaining my objects, I make the wall thickness of the burner at its gas intake end, and running the length of its operating assembly joining portion, several times greater than the wall thickness of the combustion chamber of the burner which represents that portion extending beyond the short assembly joining portion at the intake end of the burner. Thus, when the face of the combustion burner at its gas intake end is securely assembled to and butted against the mating face and attaching means of the operating assembly of the pressure generating tube, this procedure makes for unbroken and continuous heat conductivity by reason of the intimate contact of said face and attaching means, as well as securely sealing both of said faces and said attaching means against gas pressure or other leakage.

This burner is constructed in such a manner that the operating assembly of the pressure generating tube extends for a suitable length into the gas intake end of the burner so that the instant the gas reaches and passes through the thickened and superheated wall portion at the gas intake end of the burner it becomes intensely super-volatilized and suddenly expands into the

2

combustion chamber of the said burner and mixes with the air therein to provide ideal combustion, thus putting great force behind the blast flame emitting therefrom.

- 5 The elements that bring about this intense super volatilization of the gases are the large diameters of the butting faces of the burner and the operative assembly of the pressure generating tube and the thickened wall portion of the gas intake end of the burner, both of which combine with each other for ideal and maximum heat conduction at the critical assembly point, just prior to the point where the gas enters into the combustion chamber of the burner.
- 10 In the combustion burners used heretofore the wall thickness of the inside diameter was generally uniform throughout. In my burner, the greatly thickened gas intake end provides for the maximum conduction of heat to the point where it is most needed to provide maximum super heating of the gases when passing through that area for the purpose of promoting ideal combustion. The connection presently used between the pressure generating tube and the combustion burner is the jet unit covered by my prior Patent No. 2,102,404, but in which the gas expansion chambers are tapered to promote accelerated gas expansion.
- 15 As a result of the aforesaid construction, it will be noted that during the period when the combustion burner is approaching or reaches its maximum blast flame force and intensity, the force and intensity of the blast flame is such as to prevent to a very substantial degree the heat conductivity loss now apparent in the conventional type burner.
- 20 Other objects and advantages will appear as this description proceeds.
- 25 In the accompanying drawing wherein I have shown a preferred embodiment of my invention:
- 30 Fig. 1 is an enlarged section through my burner showing it in operative position upon a portion of a pressure generating tube.
- 35 Fig. 2 is a perspective view at the gas intake end of the burner, and showing the coupling unit assembled thereto.

Fig. 3 is a view showing my burner applied to a torch of conventional type, and

- 40 Fig. 4 is a perspective view at the gas intake end of the burner, with the coupling unit omitted.
- 45 Although not restricted to such use, my burner is particularly useful with a coupling or jet unit such as shown in my prior Patent No. 2,102,404, dated December 14, 1937. Such jet unit opera-
- 45

tively connects the burner and the pressure generating tube to one another and provides a continuous and unbroken path for the conduction of heat from the burner to a point well back of the jet orifice of the plug.

I have indicated generally at 10 my novel burner. It consists of a tube perforated as at 11 and provided at its inner end with a thickened wall portion, which may be an internal sleeve or tubular insert or flange 12 of metal or other suitable material of high heat conductivity.

The outer face of the insert or flange 12 provides a tight sealing and continuous high heat conducting and retaining surface by which the heat conduction and retention is increased until the blast flame emitted from the combustion chamber 13 of the burner reaches its maximum force and heat intensity.

Sleeve 12 may be permanently assembled within the burner tube in any desired manner, as by pressing or otherwise. It may be of any desired thickness and length but preferably is of a thickness and length to provide at the gas intake end of the burner a pre-heating zone or area of greater thickness, and providing greater heat retaining properties, than the combustion chamber of the burner which is of a considerably reduced wall thickness.

Insert 12 is preferably internally threaded as at 14 to enable the burner to be removably assembled to the outer end of the pressure generating tube assembly 15, but I may provide other means for removably assembling the burner to the said tube.

As shown the burner is assembled to the tube 15 by means of the jet unit 16. It comprises a central sealing collar 17 which is faced off as a hexagonal or other shaped nut and has two flat faces, one of which abuts the face at the outer end of the pressure generating tube and the other of which abuts the face of the burner and the insert 12 at its intake end. The jet unit is provided with a jet orifice 18 extending centrally therethrough. At either side of collar 17 are tubular extension 19 and 20, which provide separate tapered chambers 21 and 22 communicating with each other through orifice 18 and with the adjacent ends of the tube 15 and burner 10 respectively. Extensions 19 and 20 are preferably externally threaded as at 23 and 24 to cooperate, respectively, and preferably, with an internal series of threads 25 on the adjacent end of the tube 15 and the internal series of threads 14 on the insert 12 of the burner.

The gas intake end of tube 15 may be assembled with any suitable pressure generating unit, such as shown at 27 in Fig. 3, and the tube may be provided with any suitable wicking or other capillary means, in this instance designated as at 28.

Preferably the burner 10 is of an outside diameter at its gas intake end at least sufficiently greater than the overall diameter of the sealing collar 17 to substantially or completely overlap said face (see Fig. 2). This insures a positive tightness of seal between the face of the gas intake end of the burner and the adjacent face of the collar 17 which effectively prevents leakage of gas or other pressures or any appreciable loss of heat past the attaching means which connect the burner to the tube assembly 15, thus assuring maximum heat conductivity back to the pressure generating unit.

With this type of construction not only are the attaching means tightened up and abutted

against each other but also the aforesaid faces are tightly abutted against each other, thus creating an assembly where two separate means of tightening cooperative with each other to establish a most secure double seal action.

Another advantage of my present burner is that the insert 12 increases the thickness of the burner at its gas intake end where it overlaps the threaded portion 20 of the jet unit, and thereby provides a greater amount of metal in this region of the torch for absorbing and retaining heat from the burner when the torch is operating and for conducting the heat to the pressure generating unit and also to the wall of the fuel casing, thus greatly increasing the efficiency of vaporization of the fuel and insuring a greater volume and a more perfect combustion of the gases within the combustion chamber of the burner.

The unique construction as embodied in my combustion burner lends itself to making combustion burners of much larger diameters than was heretofore possible that will successfully and efficiently operate when used in connection with pressure generating units.

It will further be noted that I am able to use a burner tube of uniform thickness throughout its extent while at the same time obtaining the benefit of greater heat conductivity at the gas inlet end of the burner tube, due to the increased thickness of the metal at this area provided by the insert 12.

It is to be especially noted that my novel arrangement of the insert or flange 12 provides a continuous balanced heat conductivity that is substantially uniform throughout the length of the combustion burner when operating. By the foregoing arrangement the thickened wall construction of the said insert acts as a heat accumulator and retainer and thus as the discharge end of the burner reaches its maximum temperature its heat is carried back continuously to and is absorbed and continuously retained by said insert. This procedure insures that the gas intake end of the burner remains substantially as hot as its discharge end, thus giving uniform heat throughout the length of said burner and insuring that the burner will continue to fire a uniform forceful and intensive blast flame. In the conventional type of combustion burners, the remote intake end which is substantially of the same wall thickness as the discharge end cools off much quicker and retains far less heat than the discharge end of the said burner when operating. Thus it has not been possible heretofore with the conventional type of combustion burners to obtain a balanced and uniform heat throughout the length of the said burner when operating, such as I obtain with my novel type of combustion burner.

It is to be understood that various modifications of my invention may be made within the scope thereof as defined by the appended claims.

I claim:

1. In combination, a pressure generating unit, a perforated combustion burner, and a jet unit for coupling the discharge end of said pressure generating unit to the gas intake end of said burner, said burner having within its gas intake end an elongated tubular heat conducting portion of substantial thickness as compared with the thickness of the burner wall and said heat conducting portion having a transverse end face disposed substantially flush with the transverse end face of the gas intake end of the burner and also having an axial opening of relatively small diam-

eter as compared with the diameter of its transverse end face, and said jet unit having a sealing collar one face of which abuts the outer end face of the pressure generating unit and the opposite face of which abuts the transverse end face of said heat conducting portion of the burner to seal the same against pressure leakage and to provide a continuous unbroken heat path to the pressure generating unit.

2. The combination of claim 1 wherein the diameter of the transverse end face of said heat conducting portion is substantially equal to that of the face of the sealing collar with which it abuts.

SAMUEL C. BRODY.
